UNITED STATES PATENT OFFICE.

FRANCIS H. WAGER, OF TROY, NEW YORK, ASSIGNOR OF ONE-HALF TO ROBERT T. EWING, OF TROY, NEW YORK.

DEMOUNTABLE WHEEL RIM.

Application filed January 22, 1926. Serial No. 83,087.

The principal object of the invention is to facilitate the changing of tires on demountable wheel-rims.

Other objects will appear in connection with the following description.

Fig. 1 of the drawings is a view in side elevation of a demountable wheel-rim embodying my invention, and shown partly broken away and in vertical section.

10 Fig. 2 is a horizontal section of the same taken on the broken line 2—2 in Fig. 1.

Fig. 3 is a similar section taken on the broken line 3—3 in Fig. 1.

15 Fig. 4 is a plan view of the inner side of the smaller segment of the rim detached.

Fig. 5 is a central vertical longitudinal section of the same taken on the broken line 5—5 in Fig. 4.

20 Fig. 6 is a view similar to Fig. 1, of a demountable wheel-rim showing a modified form of the invention, also showing partly in side elevation and partly in longitudinal central section a turnbuckle adapted to be used for spreading and also for drawing together the ends of the larger segment of the rim.

Fig. 7 is a horizontal section of the same taken on the broken line 7—7 in Fig. 6.

30 Fig. 8 is a similar section taken on the broken line 8—8 in Fig. 6.

Fig. 9 is a plan view of the inner side of the smaller segment of the rim detached.

35 Fig. 10 is a central vertical longitudinal section of the same taken on the broken line 10—10 in Fig. 6.

40 Referring to Figs. 1 to 5 inclusive of the drawings my improved demountable wheel-rim is made up of two segments, 1 and 2, the segment, 1, comprising a much greater arc than the segment, 2.

The segment, 1, is made of resilient metal permitting its ends to be forced apart or forced together as occasion may demand in changing tires.

45 I have shown the clincher type of rim, but the cross sectional form of the rim is immaterial for the purposes of the present invention, and the sides may be straight instead of guttered if desired.

50 The side portions of the two segments, 1 and 2, abut against each other end to end along inwardly convergent lines, 3, as shown in Fig. 1, forming at each end of each segment mutually abutting surfaces which pre-

vent inward displacement of the smaller 55 segment, 2.

The smaller segment, 2, has at each end of its body portion a tongue, 4, which laps on the inner side the neighboring end of the body portion of the larger segment, 1, forming mutually abutting surfaces which prevent outward displacement of the smaller segment, 2.

These mutually abutting surfaces are preferably formed by bevelling the outer 65 surfaces of the tongues as shown at 5, and by similarly bevelling the inner side of the body portion of the larger segment as shown in Fig. 1, whereby the lap-joint formed by the tongue, 4, and the lapped portion of the body of the segment, 2, is maintained of the same thickness as the body of the rim, and within the normal cross-sectional dimensions 70 of the rim.

The smaller segment, 2, is thus interlocked 75 at each end with the respective ends of the larger segment, 1, by integral interengaging means whereby displacement of said smaller segment, 2, either inwardly or outwardly is prevented.

With the segment, 2, thus inserted between, and interlocked with, the ends of the segment, 1, a complete rim is formed adapted to support a pneumatic or other tire in the usual manner.

80 The tire when applied to the rim forms an additional means for holding the two segments together as it closely encircles the body of the rim and tends to prevent expansion of the segment, 1, which is necessary to release of the segment, 2, because to release said segment in an inward direction the ends of the segment, 1, must be spread apart a sufficient distance to release the lock formed by the convergent mutually abutting surfaces along the convergent lines, 3, while to release said segment in an outward direction the ends of the segment, 1, must be spread apart a sufficient distance to release the lock formed by the mutually abutting surfaces of the tongues, 4, and the ends of the segment, 1.

85 When the rim is secured in place upon a wheel the circumferential portion of the wheel forms an additional protection against inward displacement of the segment, 2.

90 The operation of the device is as follows: To apply a tire to the rim, the segment, 1,

is expanded in any known manner until the lock formed by the tongues, 4, is released whereupon the segment, 2, can be outwardly withdrawn.

5 The segment, 1, is then contracted by any suitable means to permit the tire to be readily applied thereto, the tire being at the same time applied to the segment, 2, which will temporarily occupy a somewhat outwardly displacement position.

10 After the tire has been thus applied, the segment, 1, is again expanded until the tongues, 4, on the segment, 2, can be passed between its ends.

15 The segment, 1, is then permitted to contract to normal position interlocking the tongues, 4, with the ends of the segment, 1, and completing the rim formation.

20 The tire is then inflated and the device is ready to be applied to a vehicle wheel in the usual manner.

If preferred, the segment, 1, may be expanded to a greater degree sufficient to release the lock formed by the mutually abutting surfaces along the lines, 3, affording abutment room for applying the segment, 2, to the tire which has already been applied to the segment, 1, in which case all that is necessary is to maintain the ends of the segment, 2, in position to properly abut against the neighboring ends of the segment, 1, as the segment, 1, is permitted to contract in order that the tongues, 4, shall properly engage the inner sides of the neighboring ends of the segment, 1.

25 To remove the tire, the segment, 1, is expanded by any suitable means until the lock formed by the mutually abutting surfaces along the lines, 3, is released, whereupon the segment, 2, can be released from the tire and removed by inward displacement. The segment, 1, is then contracted sufficiently to permit the tire to be easily removed therefrom.

30 40 The construction shown in Figs. 6 to 10 inclusive is the same in all respects as that above described, except that the body portion of the segment, 2^a, and the neighboring ends of the segment, 1^a, are each formed 105 with a plurality of tongues, 6, on the segment, 2^a, and 7 on the segment, 1^a.

45 50 55 Alternate tongues, 6, on the segment, 2^a, lap on the outer side respective tongues, 7, on the segment, 1^a, and the other tongues on the segment, 2^a, lap on the inner side the respective other tongues on the segment 1^a.

60 The mutually abutting surfaces on these respective tongues are preferably beveled whereby the combined thickness of two mutually lapping tongues is not greater than the thickness of the body of the rim.

65 70 75 Mutually abutting surfaces on these respective tongues thus prevent both inward displacement and outward displacement of

the segment, 2, and the tongues by sidewise engagement tend to hold the two segments in circular alignment.

I have shown in Figs. 6 and 7, a convenient form of turnbuckle for use in expanding and contracting the segment, 1, for the purposes above set forth.

75 This comprises a nut member, 8, and right and left hand screw threaded members, 9 and 10, each of which has on its outer end a hook, 11, formed with two prongs adapted to respectively engage two holes, 12, formed in the body portion of the segment, 1, a short distance from each end of said segment; but any rim expanding and contracting mechanism may be used.

80 In beveling the ends of the segment, 1, to receive the bevelled tongues, 4, of the segment, 2, channels are formed on the inner side of the body portion of the segment, 1, within which channels said tongues, 4, are seated and the side walls of these channels and the side walls of the tongues are thus formed with mutually abutting surfaces which prevent lateral displacement of the segment, 2.

85 The two segments may be provided in any known manner with mutually abutting surfaces to prevent lateral displacement of the segment, 2, but I prefer to obtain this result by beveling the tongues, 4, and the seats therefor in the segment, 1, as by such a construction the engaging portions of the two segments are confined within the normal cross-sectional dimensions of the rim.

90 I do not wish to be limited to the constructions shown and above described, as, for certain purposes of the invention, various changes may be made in the form and arrangement of various parts of the device without departing from the spirit of the invention.

95 What I claim as new and desire to secure by Letters Patent is—

to prevent lateral displacement of the ends of one segment relatively to the ends of the other segment.

3. A demountable wheel rim comprising
5 two separable segments abutting each other
end to end, and having lapping portions
mutually abutting to prevent of themselves
both inward and outward displacement of
each end of each segment relative to the
10 neighboring end of the other segment, said

lapping portions having mutually abutting
surfaces serving also to prevent lateral dis-
placement of the ends of one segment rela-
tively to the ends of the other segment, and
said lapping portions being so formed as to 15
be confined within the normal cross-sectional
dimensions of the rim.

In testimony whereof, I have hereunto set
my hand this 16th day of January, 1926.

FRANCIS H. WAGER.
